[57] CLAIM

The ornamental design for an ice bucket, as shown and described.

DESCRIPTION

FIG. 1 is an elevational view of one side of an ice bucket showing my new design;

FIG. 2 is an elevational view thereof of the side opposite that shown in FIG. 1;

FIG. 3 is a top plan view thereof;

FIG. 4 is a bottom plan view thereof;

FIG. 5 is a top perspective view thereof with the cover in an open condition; and

FIG. 6 is an elevational view of a modification of my new design of FIG. 1 with the cover in an open condition. The sides, top, and bottom views of this design, in a closed condition, are identical to those views shown in FIGS. 1-4.

FIG. 1.

FIG. 2.

FIG. 3.

FIG. 5.

FIG. 4.

FIG. 6.
